PROCESS FOR SEPARATION OF ALKYL PHENOLS
BY AZEOTROPIC DISTILLATION WITH A NON-POLAR BRANCHED ALKENELouis L. Parisse, Oil City, Pa., assignor to Koppers Company, Inc., a corporation of Delaware
Filed Dec. 9, 1966, Ser. No. 600,492
7 Claims. (Cl. 203—52)

ABSTRACT OF THE DISCLOSURE

Polar alkyl phenols preferentially azeotrop with a non-polar branched alkene so that the azeotroped alkyl phenol is separable by distillation from less polar alkyl phenols. The nonpolar branched alkene should have about 12 carbon atoms and its boiling point should be within 30° C. of the alkyl phenol with which it is to azeotrop.

Background of the invention

This invention relates to a process for the separation and purification of alkyl phenols, particularly, to the separation of alkyl phenols from a mixture of alkyl phenols having close boiling points but differing degrees of polarity by adding to the mixture an azeotroping agent which preferentially azeotropes at least one of the alkyl phenols.

Mono and polymethyl phenols are naturally occurring phenols found in coal tar distillates such as derived from bituminous coal. Dimethyl phenols, as well as trimethyl phenols, are also obtained as by-products in the alkylation of phenol to produce 2-methyl phenol (*o*-cresol). The dimethyl phenols exist in six isomeric forms, as do also the trimethyl phenols.

Certain of the methylphenol isomers are valuable as intermediates for the synthesis of, for example, antioxidants, while others may be used as polymerizable monomers. For example, 2,6-dimethyl phenol is a valuable isomer which is used in the preparation of aromatic polyethers such as polyphenylene oxide. It is therefore desirable to obtain the isomer in a highly purified form. Unfortunately, when 2,6-dimethyl phenol is produced synthetically or is produced from coal tar distillates, monomethyl phenols (cresols) are present. For example, when 2,6-dimethyl phenol is present in what is called the cresol distillate or fraction of coal tar by-product—named for the monomethyl phenols (cresols) which are in this fraction—it is almost impossible to separate the 3-methyl phenol and 4-methyl phenol from the dimethyl phenol by ordinary distillation techniques due to the close boiling points of the compounds. (201° C. for 2,6-dimethyl phenol, 202.8° C. for 3-methyl phenol, and 202.5° C. for 4-methyl phenol.)

Summary of the invention

It has now been discovered that alkyl phenol mixtures having very close boiling points may be separated by the addition of a branched alkene azeotroping agent to the mixture.

In accordance with the invention, alkyl phenols having close boiling points may be separated by:

(a) Adding to a mixture of alkyl phenols wherein at least one alkyl phenol is more polar than the others, a nonpolar branched higher alkene having a boiling point

2

within about 30° C. of the more polar alkyl phenol to form an azeotrope of the alkene and the more polar alkyl phenol.

(b) Distilling the mixture to separate the azeotrope 5 from the less polar alkyl phenol.

Detailed description

While the exact mechanism by which the alkene preferentially azeotropes with one or more of the alkyl phenols 10 is not completely understood, it is believed that the alkene, being a nonpolar molecule, is preferentially attracted to the most polar alkyl phenol or phenols, for example, to 3-methyl phenol and 4-methyl phenol rather than 2,6-dimethyl phenol due to the steric hindrance and thus low 15 polarity of the 2,6-dimethyl phenol.

The branched higher alkenes useful in this invention are those having from 10-14 and preferably 12 carbon atoms. The particular alkene selected should have a boiling point 20 within about 30° C. of the polar alkyl phenol with which it is to form an azeotrope.

Examples of suitable branched higher alkenes are those formed by trimerization of methylpropene (iso-butylene). These trimers boil at about 175-177° C. and have a specific gravity at 60° F. of 0.763. Conveniently, they may be 25 obtained as a by-product in the butylation of cresols with isobutylene to produce butyl-cresols. If the trimer is obtained in this fashion, it may be purified to remove cresylic impurities by caustic scrubbing followed by fractional distillation.

30 The alkene polar alkyl phenol azeotrope contains about 80-90% by weight alkene at atmospheric pressure. It is therefore necessary, when the distillation is conducted at atmospheric pressure, to use amounts of alkene in a weight ratio to the polar alkyl phenol with which it is to azeotrope 35 of at least 6 to 1. However, since the weight percent of the trimer in the azeotrope decreases with pressure, lesser amounts of trimer can be used if the distillation is carried out at higher pressures. It is preferable to add an excess 40 of alkene usually about 10 to 1 to 20 to 1 for atmospheric distillations. The excess alkene is then removed in the distillation after the alkene-polar alkyl phenol azeotrope. Some of the less polar alkyl phenol may also come over in this fraction in which case, the fraction may be recycled 45 to increase the overall yield.

45 After the azeotropic distillation the azeotroped alkyl phenol may be separated from the alkene by conventional means such as steam distillation or crystallization.

The accompanying flow sheet and the following examples 50 will serve to further illustrate the practice of the invention.

EXAMPLE I

200 grams of a C₁₂ branched alkene (trimer of isobutylene) was added to 200 grams of a mixture of 2,6-dimethyl phenol and monomethyl phenols which had been previously analyzed and found to contain 91.5% 2,6-dimethyl phenol, 1.9% 2-methyl phenol and 6.6% 3-methyl phenol and 4-methyl phenol. The mixture was pumped to a still 55 equipped with a helix packed distillation column. The mixture was distilled at atmospheric pressure with a 19:1 reflux ratio. The first series of cuts were collected up to a boiling point at 176° C. A second series of cuts were then collected between 176° and 200° C. The third series 60

of cuts were collected at 201° C. Analysis of the fractions by vapor phase chromatography revealed the following constituents:

one alkyl phenol that is more polar than the other in the mixture comprising:

(a) adding to said mixture a nonpolar branched higher

TABLE I

Fraction	Boiling Point, °C.	Weight (grams)	Weight (percent)	Area Percent Composition			
				C ₁₂ Trimer	2,6-dimethyl phenol	2-methyl phenol	3-methyl phenol, 4-methyl phenol

Fractions 1-4 contained almost all of the monomethyl phenols while fractions 10 and 11 were essentially pure 2,6-dimethyl phenol. Fractions 5-9 are suitable for recycle back to the still or the alkene may be separated from the 2,6-dimethyl phenol by steam distillation.

Similar results are obtained when the weight ratios of trimer to monomethyl phenol impurities are varied from 6 parts by weight trimer per part by weight monomethyl phenol mixture to 20 parts by weight trimer per part by weight of monomethyl phenol.

EXAMPLE II

The pure 2,6-dimethyl phenol obtained in the third series of cuts (fractions 10-11) in Example I was further tested for purity by obtaining the freezing point of the material. A portion of the liquid was placed in a test tube equipped with a stirrer and a thermometer. The test tube was immersed in an ice bath while the contents were stirred. When definite crystallization was started, stirring was stopped and the freezing point considered to be the maximum temperature reached after super cooling. The freezing point was found to be 45.5° C.

The foregoing has presented a novel process for the separation of polar alkyl phenols from nonpolar alkyl phenols which have hitherto been very difficultly separable. The process allows, for example, 2,6-dimethyl phenol to be separated from monomethyl phenols with very little loss of 2,6-dimethyl phenol.

What is claimed is:

1. A process for the separation of at least two alkyl phenols having close boiling points but containing at least

alkene having from 10-14 carbon atoms and a boiling point within 30° C. of the said more polar alkyl phenol to form an azeotrope of the alkene and the said more polar alkyl phenol; and

(b) distilling the azeotrope from said mixture to separate the more-polar alkyl phenol from the less polar alkyl phenol.

2. The process of claim 1 wherein the nonpolar branched alkene has 12 carbon atoms.

3. The process of claim 2 wherein the nonpolar branched alkene consists essentially of trimers of methylpropene.

4. The process of claim 3 wherein the mixture of alkyl phenols comprises 2,6-dimethyl phenol and monomethyl phenols.

5. The process of claim 4 wherein the trimers of methylpropene have a boiling point range of 175-177° C. and a specific gravity at 60° F. of 0.763.

6. The process of claim 5 wherein the amount of trimer is from 6 to 20 times by weight of the weight of the monomethyl phenols present in the alkyl phenol mixture.

7. The process of claim 1 wherein said morepolar alkyl phenol is separated from said nonpolar branched higher alkene after the distillation.
